(57) **CLAIM**

The ornamental design for a luggage wheel fork with a wheel, as shown and described.

DESCRIPTION

FIG. 1 shows a front perspective view of a luggage wheel fork with a wheel;

FIG. 2 shows a right elevation view of the luggage wheel fork with a wheel of FIG. 1;

FIG. 3 shows a left elevation view of the luggage wheel fork with a wheel of FIG. 1;

FIG. 4 shows a front elevation view of the luggage wheel fork with a wheel of FIG. 1;

FIG. 5 shows a rear elevation view of the luggage wheel fork with a wheel of FIG. 1;

FIG. 6 shows a top view of the luggage wheel fork with a wheel of FIG. 1; and,

FIG. 7 shows a bottom view of the luggage wheel fork with a wheel of FIG. 1.

The broken lines in FIGS. 1-7 illustrate the environment of the luggage wheel fork with a wheel and form no part of the claimed invention.
